CLOSURE

James N. Halkett, Cleveland Heights, Ohio, assignor, by mesne assignments, to Eaton Detroit Metal Company, Cleveland, Ohio, a corporation of Ohio

Application September 6, 1933, Serial No. 688,346

4 Claims. (Cl. 70—90)

This invention relates to closure devices for gasoline tanks, radiators, and other forms of containers and, more particularly, to improvements therein whereby the closure may be locked in position.

It is one of the objects of the invention to provide a locking device for use in connection with the commercial types of closures wherein the closure is held in position by securing means.

10 A further object of the invention is to provide a locking closure embodying the ordinary cap and an ornamental cover therefor, in which the cover is freely rotatable with respect to the cap when the closure is locked.

15 A further object of the invention is to provide a locking closure embodying the ordinary cap and an ornamental cover therefor, and in which the locking mechanism is adapted to secure the cover against rotation relative to the cap so as to permit the closure to be used as an ordinary nonlocking closure or to permit the cover to be freely rotated relative to the cap when the latter is locked in position.

20 Other objects of the invention and the features of novelty will be apparent from the following description taken in connection with the accompanying drawings, of which

25 Figure 1 is a plan view of a closure device embodying one of the preferred forms of my invention;

30 Fig. 2 is a transverse section thereof on the line 2—2 of Fig. 1;

Fig. 3 is a transverse section on the line 3—3 of Fig. 1;

35 Fig. 4 is a detail section on the line 4—4 of Fig. 3;

Fig. 5 is a view similar to Fig. 4 but showing a slightly modified construction;

40 Fig. 6 is a plan view, similar to Fig. 1, of another preferred form of my invention;

Fig. 7 is a transverse section on the line 7—7 of Fig. 6;

Fig. 8 is a transverse section on the line 8—8 of Fig. 6; and

45 Fig. 9 is a detail section on the line 9—9 of Fig. 8.

Referring to Figs. 1 to 3, this form of the invention is illustrated with the parts in their locked position, wherein the cover for the cap is freely rotatable on the latter. In these drawings, 10 indicates a common form of a tubular neck such as is used on a gasoline tank or radiator of an automobile. This neck is provided with an internal flange 11 having the usual openings 12 and the depending cams 13, the latter cooperating with the fingers 14 on the cap to clamp the cap in position. The cap comprises a hollow stamped shell 15 having a laterally projecting flange 17 at its upper end which engages a gasket 18 that is seated on the flange 11 and seals the

filler neck opening. The locking fingers 14 are secured against the bottom wall of the shell 15 by rivets 19.

A lock barrel 20 is arranged on the upper side of the bottom wall of the shell 15 and is provided with a threaded extension 21 which extends through the bottom wall, and a nut 22 and lock washer 23 are employed to rigidly secure the barrel 20 to the shell. The barrel 20 has a laterally projecting flange 24 and the inner wall 25 of the cover, for the cap, is loosely arranged between this flange 24 and the flange 17, of the shell, so as to be rotatable with respect to the cap. The wall 25 has a downwardly extending flange 26 at its inner periphery which surrounds the barrel 20.

The cylinder 27, of the lock proper, is rotatably arranged in the barrel 20 and provided with the usual tumblers 28 which are adapted to engage with the slots 29 in the barrel to hold the cylinder against rotation relative to the barrel. A sliding bolt 30 is arranged in a slot 31 at the upper end of the barrel 20 and is provided with a lip 32 with which a finger 33, on the cylinder 27, cooperates to move the bolt 30 to the left, from its position in Fig. 3. A spring 34, carried by the barrel 20, engages with the lip 32, as best shown in Fig. 4, and is adapted to move the bolt 30 to the right in Fig. 4.

A plate 35 is arranged on the upper end of the barrel 20 and provided with a boss 36, at its inner periphery, which engages with a collar 37, on the cylinder 27, to hold the latter in the position shown in Figs. 2 and 3.

The cover of the closure comprises, in addition to the inner wall 25, an outer wall 38 which may be suitably shaped for purposes of ornamentation. As illustrated, the outer wall 38 has a depending peripheral flange 39 which fits over and is secured to a peripheral flange 40 on the inner wall 40. The central portion of the outer wall 38 fits upon the plate 35 and has a central opening 41 which surrounds the boss 36.

The inner wall 25 of the cover is provided with a series of stamped up lugs 42 which are arranged in spaced relation about the flange 24 of the barrel 20 and the end portion 43 of the bolt 30 is adapted to enter the spaces between the lugs 42 and thereby hold the cover against rotation relative to the cap. When the cover is so held, the cap and cover may be rotated as a unit to move the fingers 14 over the cams 13 to secure the cap in position on the neck or to disengage the fingers 14 from the flange 11 and permit the removal of the cap from the neck. A key 44, when inserted in the cylinder 27, withdraws the tumblers 28 from the slots 29 so as to permit rotation of the cylinder relative to the barrel 20. When the cylinder is rotated in one direction the finger 33 thereon

engages with the lip 32 on the bolt 30 and withdraws the bolt to the position shown in Fig. 4. When the bolt is in this position it cannot engage with the lugs 42 and therefore the cover 5 will be freely rotatable with respect to the cap and the cover cannot be used as the means for rotating the cap so as to permit its removal from the neck. Withdrawal of the key 44 when the bolt 30 is in the position shown in Fig. 4, permits 10 the tumblers 28 to engage with the slots 29 and thus lock the cylinder 27.

When it is desired to remove the cap, the key 15 44 is inserted in the cylinder 27 and the latter rotated a half turn to move the finger 33 to the position shown in Fig. 3. This permits the spring 34 to move the bolt 30 toward the right and into one of the spaces between the lugs 42. If the end 43 happens to engage with one of the lugs 42, a slight rotation of the cover will effect 20 disengagement and permit the end 43 to enter the space between the lugs. The cover is thus locked to the cap and the latter may be turned by the cover as desired to either remove the cap from the filler neck or to apply it thereto. 25 By withdrawing the key 44, under these circumstances, the cylinder 27 will be again locked to the barrel 20 and the closure device may be applied to and removed from the neck like an ordinary non-locking cap.

30 In the modification illustrated in Fig. 5, a plurality of coil springs 45 are used for moving the bolt 30 instead of the single leaf spring 34 shown in Fig. 4. The advantage of this construction is that the breakage of one of the 35 springs would not seriously affect the operation of the lock.

Referring now to the form of the invention illustrated in Figs. 6 to 9, inclusive, the construction is generally similar to that above described but the locking bolt 50 is positively moved in both directions by the finger 51 on the cylinder 52. The finger 51 cooperates with the lips 53 on the opposite ends of the bolt. The slot 54, in which the bolt 50 slides, has a lateral extension 55 along one side of the bolt 50, and in this extension there is arranged a spring detent 56 which cooperates with notches 57 and 58 in the edge of the bolt 50 to hold the bolt in its locking or retracted positions. It will also be noted that the lugs 59, which are stamped up from the inner wall 60 of the cover, are V-shaped, as will be seen in Fig. 6, and the end of the bolt 50 is pointed, as will be seen from Fig. 9, so that when the bolt 50 engages with one of the lugs 59, the parts will slide on one another to permit the bolt to enter into a space between 50 two of the lugs 59.

In other respects, the two constructions are substantially the same and function substantially in the same manner. The construction illustrated in Figs. 6 to 9 has the advantage that the bolt 50 is positively actuated in both directions and is not dependent upon a spring which is liable to breakage.

60 While I have illustrated and described what I now consider to be the preferred forms of my invention, it will be evident to those skilled in the art that changes may be made in the details which have been illustrated and described without departing from the spirit of the invention, as defined in the appended claims.

Having thus described my invention, I claim:

1. In closure devices, the combination of a member having an opening, a cap for closing said opening, said cap and said member having co-operating parts whereby the cap is adapted to be secured to said member by a rotary movement, a cover rotatably mounted on said cap, a lock barrel secured to said cap, a lock cylinder rotatably mounted in said barrel and having key actuated means for securing the barrel and cylinder against relative rotation, a bolt slidably mounted on said barrel, said cover having a circular series of V-shaped lugs adapted to be engaged by said bolt to secure the cover against rotation relative to the cap, and means on said cylinder for actuating said bolt. 5

2. In closure devices, the combination of a member having an opening, a cap for closing said opening and having means to cooperate with said member to secure the cap thereto by a rotary movement, a lock barrel secured to said cap and having a laterally projecting flange, a cover for said cap comprising inner and outer walls which are secured together, said inner wall having its inner peripheral portion loosely held between said cap and said flange so as to permit the cover to be freely rotated relative to the cap, a lock cylinder rotatably arranged in said barrel, a bolt carried by said barrel, means on said cover between said walls with which said bolt cooperates 25 to lock the cover against rotation relative to said cap, and means on said cylinder for actuating said bolt. 30

3. In closure devices, the combination of a member having an opening, a cap for closing said opening and having means to cooperate with said member to secure the cap thereto by a rotary movement, a lock barrel secured to said cap and having a laterally projecting flange, a cover for said cap comprising inner and outer walls which are secured together, said inner wall having its inner peripheral portion loosely held between said cap and said flange so as to permit the cover to be freely rotated relative to the cap, a lock cylinder rotatably arranged in said barrel, a bolt 45 carried by said barrel, spaced lugs stamped from the material of said inner wall and arranged radially outward from said flange so as to be engaged by said bolt and thereby lock said cover against rotation relative to said cap, and means 50 on said cylinder for actuating said bolt. 55

4. In closure devices, the combination of a member having an opening, a cap for closing said opening and having means to cooperate with said member to secure the cap thereto by a rotary movement, a lock barrel secured to said cap and having a laterally projecting flange, a cover for said cap comprising inner and outer walls which are secured together, said inner wall having its inner peripheral portion loosely held between said cap and said flange so as to permit the cover to be freely rotated relative to the cap, a lock cylinder rotatably arranged in said barrel, a bolt carried by said barrel, spaced V-shaped lugs stamped from the material of said inner wall and arranged radially outward from said flange, said bolt having a V-shaped projection for cooperation with said lugs and whereby said cover is locked against rotation relative to said cap, and means on said cylinder for actuating said bolt. 65
